L. P. ARMSTRONG

CONVERTIBLE FURNITURE

Filed Oct. 25, 1926

INVENTOR

Lynn P. Armstrong
John A. Prasith

ATTORNEY

UNITED STATES PATENT OFFICE.

LYMAN P. ARMSTRONG, OF SAN JOSE, CALIFORNIA.

CONVERTIBLE FURNITURE.

Application filed October 25, 1926. Serial No. 143,996.

This invention relates particularly to a structure which may be converted at will into either a cot or a chair.

It is one object of the present invention to provide a structure of the character indicated that may be quickly and easily changed from a cot to a chair or a chair to a cot or any intermediate position.

It is another object to provide a structure of the character indicated that may be fixed rigidly in position or allowed to swing freely as desired.

It is still another object of the invention to provide a structure of the character indicated wherein the foot-piece may be utilized as the foot of the cot when the structure is formed into a cot and as a foot-rest when the structure is formed into a chair.

It is also an object of the invention to provide a structure of the character indicated so constructed and arranged as to be readily mounted upon any suitable support.

Finally it is an object of the invention to provide a structure of the character indicated that is economical to manufacture, that is so constructed that its head may be run out of an ordinary window, that may be used as a stretcher or operating table, that may be operated by the occupant without assistance, that may be folded for carrying, and highly efficient in its practical application.

In the drawing:

Figure 1 is a side elevation of the structure, parts being broken away.

Figure 2 is a perspective illustration of a portion of one side of the structure.

Figure 3 is a perspective illustration of another portion of one side of the structure.

Figure 4 is an enlarged section on 4-4, Figure 2.

Figure 5 is an enlarged detail plan view of the part "A" in Figure 1.

Figure 6 is an enlarged detail plan view of the part "B" in Figure 1.

Figure 7 is an elevation of one end of the structure.

Referring now more particularly to the drawing, I show at 1-2, 1-2 two pairs of crossed supporting legs connected by a bolt

3 about which they may pivot and a spacing shelf 4. In the upper end of each leg is mounted a pin as 5 for the purpose herein-after described.

55 The combination cot and chair portion of the device comprises three main section, indi-

cated generally by the letters "C", "D" and "E".

The section "C" comprises a pair of side bars as 6 connected by a head cross bar 7 to which one end of a canvas 8 is secured. On this head bar are mounted upstanding rods as 10 carrying clamping bars 11 for the purpose of holding one end of the bedding, this structure being fully described in my application filed March 4, 1926, Serial No. 92,253, entitled Clamping devices. On the end of each bar 6 remote from the head bar 7 is mounted a metal plate as 12. Each plate 12 is provided with an upstanding ear 13 at one end and on the outside of bar 6, and this ear is pivotally connected to an arm 14 as at 15. The arm 14 is provided with orifices 16 to engage pins 5 as shown. The opposite end of plate 12 is turned inwardly a distance as at 17 to engage a cross bar 18, and also is provided with an upstanding ear 19 on the inside of bar 6.

The section "D" comprises a pair of side bars as 20, each bar having an outwardly turned lower flange 21 to strengthen the same and an upwardly turned ear 22 at one end adapted to lie along side of the ear 19 on bar 12 and pivotally connected thereto by an adjustable fastener 23. The other end of the bar 20 has a downwardly turned ear 24.

The third section "E" comprises a pair of short side bars 25, each bar 25 having a plate 26 mounted on one end thereof, the bar 26 having one end turned downwardly to lie along side of the ear 24 on bar 20 to which it is pivotally connected by a fastener 27. This end of plate 26 also has a laterally extending finger 28 to which is secured a cross bar 29 thereby spacing and bracing the two side bars 25. On the opposite end of the plate 26 is a flange 30 turned to lie flat on the top of bar 25 and carrying an upstanding portion 31 forming a bearing for a rod 32 which connects and spaces the corresponding ends of the two bars 25, this rod having a ratchet 33 mounted on one end and engaging a dog 34 mounted on the flange 30. On rod 32 is mounted the lower end of the canvas 8.

On the lower ends of the bars 25 is mounted a clamping device 35 fully described in my application above referred to which serves both as a clamping device for the bedding and also as a foot rest when the device is formed into a chair. In the present

case the device consists of a pair of upstanding rods 36 mounted in bars 25 and having a cross-bar 37 mounted thereon and a second cross-bar 38 slidably mounted thereon and carrying friction plates 38^a to engage rods 36.

The fastening devices 23-27 are identical in construction and are preferably made as follows, using the connection between plates 10 20 and 26 for the purpose of illustration.

The end of bar 26 is punched outwardly as shown at 39 thereby forming a tapering portion which is internally threaded as at 40. The ear 24 is likewise punched outwardly to form an opening 41, this part also having a tapering edge, but this is left smooth to engage the outer surface of the part 39. A button 42 is provided with an inwardly turned flange on its head as shown 20 at 43, and this button is threaded as at 44 to engage the threaded portion 40 of the part 39. The inner end of the button 42 is spread slightly so as not to interfere with its loosening but to prevent its withdrawal 25 or working loose, as indicated at 45.

The canvas 8 is connected to the cross-bar 18 by means of a strip as 46 secured thereto and passing around the said cross-bar as shown clearly in Figure 2. A strong cable 30 or wire as 47 is connected to the arm 14 as shown at 48 and also to its corresponding bar 25 at a point adjacent to its pivotal end as shown at 49.

When assembled as above set forth the 35 frame may be quickly and easily arranged in any suitable position as chair or cot and the canvas stretched to the required tension. The occupant of the device may loosen or tighten the fasteners and so secure the 40 desired position.

Certain features in the construction should be more particularly pointed out.

In order to have the structure function

in the manner desired it is desirable that the side bars 14 be angularly positioned relative to a horizontal plane so that the length of the ear 13 may be short and yet the required movement is secured for element 47. Also the length of the arms 14 should be such that the elements 47 will assume a vertical 56 position when the structure is formed into a chair.

In order to prevent the folding of parts 12 and 20 beyond the desired positions either when in a horizontal position to form a cot 55 or when in a position to form a chair, I have formed stop members as indicated at 50 to limit the movement of these parts. These stop members are formed on the adjacent ends of the said members 12 and 20 60 as shown.

It is to be understood, of course, that while I have herein shown and described but one specific embodiment of the invention, changes in form, construction and 65 method of operation may be made within the scope of the appended claim.

I claim—

In a chair of the character described, the combination of a pair of upright standards, 70 an arm rigidly mounted on each standard, a frame pivotally mounted off-center on said arms and at one end thereof, side bars pivotally mounted on said frame to form a seat portion and releasable fastening means 75 therefor, side bars pivotally mounted on said last mentioned side bars and releasable fastening means therefor, means for supporting a bed bottom on said frame and side bars, and supporting connecting elements inserted between the second mentioned side bars adjacent their pivotal connections to the first bars and the ends of the arms remote from the pivotal mounting of the frame.

LYMAN P. ARMSTRONG.
